US0D1112727S

(12) **United States Design Patent** (10) **Patent No.:** **US D1,112,727 S**
(45) **Date of Patent:** **** Feb. 10, 2026**

(54) **MEDICINAL DISPENSER**

(71) Applicant: **TICKERWORKS, INC.**, Folsom, CA (US)

(72) Inventor: **Ramiro M. Perez**, Folsom, CA (US)

(73) Assignee: **TICKERWORKS, INC.**, Folsom, CA (US)

(**) Term: **15 Years**

(21) Appl. No.: **29/935,598**

(22) Filed: **Apr. 2, 2024**

(51) **LOC (15) Cl.** **24-02**

(52) **U.S. Cl.**

USPC **D24/113; D24/130**

(58) **Field of Classification Search**

USPC D24/112-114, 127-130, 133, 186; D23/209, 356, 359, 360, 366; D27/170, D27/162, 167, 194

CPC A61M 5/3156; A61M 5/31591; A61M 5/3155; A61M 5/3157; A61M 5/31501; A61M 5/14566

(57) **CLAIM**

The ornamental design for a medicinal dispenser, as shown and described.

DESCRIPTION

FIG. 1 is a front top perspective view of a medicinal dispenser;

FIG. 2 is a rear bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an exploded view thereof, shown with a reduced scale, and having an axis line having broken segments of varying length extending through the center of the medicinal dispenser, the broken axis line forming no part of the design. The dash-dot broken lines in the drawings illustrate portions of the medical dispenser and form no part of the claimed design.

1 Claim, 5 Drawing Sheets
